FRANCISCO, CALIFORNIA.

SUIT-BOX.

1,079,137.

Specification of Letters Patent. Patented Nov. 18, 1913.

Application filed October 24, 1912. Serial No. 727,484.

To all whom it may concern:

Be it known that we, IRVING H. LYONS and RAOUL J. GRUENBERG, citizens of the United States, residing at San Francisco, in the county of San Francisco and State of California, have invented certain new and useful Improvements in Suit-Boxes, of which the following is a specification.

This invention relates to that class of boxes which are usually made of paper-board or card-board, and are commonly used by tailors and others for delivery suits of clothes and for analogous purposes, and are therefore sometimes designated as suit-cases. Boxes of this class are also commonly made of two similar parts, one telescoping within the other. When such boxes or suit-cases are employed for relatively heavy garments, especially for complete suits and for overcoats, it has been found convenient to provide each of the two parts of the telescoping box with a handle for carrying the same, and also to arrange this handle in connection with a reinforcing device of angular formation applied in the box in such a manner as to reinforce and stiffen the same along the line where the edge member joins the side member of the box.

A telescoping box or suit-case provided with handles and having angle-form reinforcing members, such as above mentioned, is illustrated in Letters Patent of the United States, No. 1,027,885, granted to Raoul J. Gruenberg, May 21, 1912, for "box-handles", to which reference may be had; and our present improvements are more particularly designed for use in connection with boxes of the class described in said Gruenberg patent, and especially when such boxes are provided with locking devices at the corners so that by unlocking the corner hooks, in a well known manner now in general use, the boxes may be packed in a flat or knocked-down form in order to facilitate shipping and storing the same.

In the accompanying drawing forming a part of this specification, Figure 1 is an isometrical view of a portion of one of the parts of a suit-case or box of the class above specified, embodying our present improvements. Fig. 2 is a central sectional view transversely of the end member of the box, in the plane X—X, Fig. 1. Fig. 3 is a view similar to Fig. 2, but showing the parts folded down nearly to a flat form, as when the box is of the knock-down kind.

Similar characters designate like parts in all of the views.

In the drawing, a side-member of the box is designated by S, and one of the end-walls or edge-members by E; but only such a portion of one end of a box is shown as deemed convenient for illustrating the present improvements, other portions being broken away. A primary, angle-form reinforce, comprising the plate-form members 6 and 7, is shown applied inside the box, and extending along the adjoining edges of the box-walls, S and E. A slot may be made at 8 in the corner of the box, for the handle 5, when this connects with said reinforce 6—7; but in some instances, if desired, this handle and the slot therefor may be omitted.

A secondary reinforce, also of angle-form, consists of the plate-form members 12 and 14, and is affixed on said primary reinforce, 6—7, longitudinally thereof, and with the member 14 located at a considerable distance away from and relatively parallel to the member 7 of said primary reinforce. This secondary angle-member, 12—14, being of an extended length and applied on the primary angle-form reinforce, 6—7, operates for directly stiffening the edge-member E of the box. This is done in part by the additional thickness of the part 12 affixed throughout its length under the lateral part 6 of the primary reinforce.

A further and relatively greater additional support is afforded by the vertically disposed web 14, which acts after the manner of a rib or beam for stiffening the edge-member E against being flexed downwardly by any load which may be carried by said web 14, or be otherwise brought to bear on said box-member E. For increasing this supporting action, the secondary reinforce 12—14, may be extended, in practice, to any length found desirable for meeting the requirements in any given case. The reinforce member 7 being joined, in the preferred construction herein shown, by the transverse plate-form member 6 with the reinforce web or rib 14, these two relatively parallel members 7 and 14, together with their said connection 6, constitute a compound reinforce which has the sectional form of a channel-bar, (see Fig. 2), and is therefore exceptionally effective as a reinforce for stiffening the flexible box wall E. The reinforce web 14 may be of such depth, measured downwardly from the plate

6.—and considering the edge-member E as being the top of the box,—as may be needed for supplying sufficient stability in the combined members. In practice, we prefer to 5 make that depth or width of the member 14, at least equal to the width of the member 7. In the drawing said member 14 is shown extended, as at 14*, and this extension is shown provided with a series of holes, as h, 10 as one suitable means whereby to tie on, or otherwise attach or connect thereto, any goods or articles within the box. Thus the member 14, with its attaching flange 12, constitute a combined reinforce and load-car- 15 rier, and these are shown formed in a single piece. Where the edge-member of the box is joined with the box-side, the primary angle-form reinforce extends along and reinforces the joined edges of said box mem- 20 bers, so that the secondary angle-form reinforce,—which is located at a distance from the box-side,—constitutes one side of a compound reinforce which has a channel-bar sectional form, and has its separated plate- 25 form portions located in substantially parallel planes and in the direction of the load-carrying stress, and vertically to said edge member E of the box.

When the box is of the knock-down kind, 30 the corners may be detachably connected in the usual way by hooks, of which one of a well-known form is indicated at k, Fig. 1. In this kind of boxes, the line of juncture at 9, is a bending-joint, and the reinforce 35 members will also each of them have a similar bending-joint connection longitudinally thereof. By these means, the primary reinforce, 6—7, and the secondary reinforce, 12—14, are each foldable, concurrently with 40 the box-sides, so that on unfolding the box, the box walls together with the channel-bar form of compound reinforce, may all be unfolded together into the compact and flat-form illustrated in Fig. 3.

45 Having thus described our invention, we claim:

1. In a garment receptacle, the combination, with a box having an edge-member joined with the side-member, and with a 50 primary angle-form reinforce comprising two plate-form portions secured respectively to the edge-member and side-member of the box, and extending along and reinforcing the joined edges of said box-members, of a 55 combined reinforce and load-carrier connecting along its attaching end with the primary-reinforce plate which is secured to said edge-member, and having its said attaching end in an angle-form constituting a second- 60 ary reinforce located at a distance from the box-side, the secondary reinforce and the primary reinforce together constituting a

compound reinforce of channel-bar sectional form and having its separated plate-form portions located in substantially parallel planes and in the direction of the load-carrying stress, and perpendicular to said edge-member of the box, substantially as described.

2. In a garment receptacle, the combination, with a box having an edge-member jointed with the side-member and with two jointed plate portions secured respectively to the edge-member and side-member of the box, and forming, when the box is folded up, 70 a foldable angle-form primary reinforce along the jointed edges of said box-members, and having a bending joint adjacent thereto, of a combined reinforce and load-carrier connecting along its attaching end with the 75 primary-reinforce plate which is secured to said edge-member, and while the box is folded up for use having its said attaching end in an angular form constituting a sec- 80 ondary reinforce, and located at a distance 85 from the box-side so that on unfolding the box to a plate-form, the two said angle-form reinforce members are also unfolded to a flat form while the said attaching end is folded down against the edge member of the 90 box.

3. In a garment receptacle, the combination, with a box having an edge-member jointed with the side-member and having a handle-receiving slot at the joint, of the 95 handle, extending outwardly through said slot and within the box having two jointed plate portions secured respectively to the edge-member and side-member of the box, and forming, when the box is folded up, a 100 primary angle-form reinforce along the slot; and a load-carrier having its attaching end affixed to the reinforce plate which is se- 105 cured to the edge-member, and having a bending joint adjacent thereto, and while the box is folded up for use having its said attaching end in an angular form constituting a secondary reinforce, and located at a 110 distance from the box-side so that on un- folding the box to a flat form, the two said angle-form reinforce members are also un- folded to a flat form while the load-carrier is folded down against the side member of the box.
